CLAIM

The ornamental design for a detail of a wrist watch, as shown and described.

DESCRIPTION

FIG. 1 is a top view of a detail of the wrist watch.

FIG. 2 is a bottom view of a detail of the wrist watch.

FIG. 3 is a right perspective view of a detail of the wrist watch.

FIG. 4 is a perspective view of a detail of the wrist watch.

FIG. 5 is a front perspective view of a detail of the wrist watch.

FIG. 6 is a bottom perspective view of a detail of the wrist watch.

FIG. 7 is a bottom right perspective view of a detail of the wrist watch; and,

FIG. 8 is a left side perspective view of a detail of the wrist watch.

The broken lines depict environment only and form no part of the claimed design.

1 Claim, 8 Drawing Sheets
